US0D1079851S

(12) United States Design Patent (10) Patent No.: US D1,079,851 S
(45) Date of Patent: * Jun. 17, 2025

(54) DUMBBELL SANDBAG

(71) Applicant: Hui Jiang, Jiangxi (CN)

(72) Inventor: Hui Jiang, Jiangxi (CN)

() Term: 15 Years

(21) Appl. No.: 29/982,566

(22) Filed: Jan. 7, 2025

(51) LOC (15) Cl. 21-02

(52) U.S. Cl.

USPC D21/681

(58) Field of Classification Search

USPC D21/803, 798, 788, 787, 771, 698, 694, D21/686, 681, 682, 680, 662, 678; D9/668, 702-714, 429-432, 645; D7/213, 601-602, 514, 521, 300.2, 624; D24/207, 118, 129, 1

(57) CLAIM

The ornamental design for a dumbbell sandbag as shown and described.

DESCRIPTION

FIG. 1 is a perspective view of a part of dumbbell sandbag showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the dumbbell sandbag and form no part of the claimed design.

1 Claim, 8 Drawing Sheets
